UNITED STATES PATENT OFFICE.

ORWELL C. REEVES, OF TOLEDO, OHIO.

DRYING APPARATUS.

Application filed January 24, 1921. Serial No. 439,412.

To all whom it may concern:

Be it known that I, ORWELL C. REEVES, a citizen of the United States, residing at Toledo, in the county of Lucas and State of Ohio, have invented certain new and useful improvements in Drying Apparatus, of which the following is a specification.

My invention relates to drying or moisture extracting apparatus, and has for its primary object the provision of a portable drying cabinet arranged for conveniently and efficiently drying clothes or other articles.

A further object of my invention is to arrange a series of apertured pipes to force heated air or steam through the articles to be dried while such articles are enclosed within a portable cabinet.

Another object of my invention is to support the articles to be dried upon screens maintained in separated position to prevent injury to the articles by crushing.

A further object is to provide a cabinet rotatable to any desired position and composed of connected sections that may be opened for convenient insertion or removal of the articles to be dried and the supporting screens.

Other objects and advantages will be apparent from the following description, in which reference is had to the accompanying drawings illustrating a preferred embodiment of my invention and wherein similar reference numerals designate similar parts throughout the several views.

In the drawings:—

Figure 1 is a perspective view of my improved drying apparatus;

Figure 2 is a side elevation thereof showing the cabinet in full lines in one position and in dotted lines in another position and with the cover opened;

Figure 3 is a central section through the cabinet;

Figure 4 is a horizontal section taken substantially on the line 4—4 of Figure 3;

Figures 5 and 6 are detail views of one of the screens used in my apparatus.

Figure 7 is a detail sectional view of one of the trunnions on which the cabinet is

pivoted and through which the pipe connection is made; and

Figure 8 is a detail view showing the manner of folding sheets or long articles about a series of screens.

55

Referring to the drawings, the numeral 5 designates a cabinet of any desired contour centrally mounted upon trunnions 6 journaled in standards 7 preferably provided with rollers or casters 8 to enable the ready movement of the cabinet to any desired position for use and its return to a closet or corner when not in use. A hinged top or lid 9 provides access to the interior of the cabinet and is preferably held in closed position when desired by a latch 10. As best shown in Figures 3 and 4, the end walls of the cabinet are formed with stepped ledges or supports 11 upon which rest the end portions 12 of a series of screens 13 which carry the clothes or other articles to be dried. The screens are preferably formed with their end portions 12 of greater thickness than the side bars 14 connecting their opposite extremities (see Figure 5) and a porous fabric is stretched around the side bars to form a support for the clothes, etc., to be dried, a space being thus provided between the fabrics of adjacent screens for the reception of the clothes or other articles, while eliminating the possibility of crushing the articles between the screens. While the fabrics of the screens are tightly stretched, they have sufficient flexibility to permit the bulging of one fabric to accommodate a layer of clothes, etc., that slightly overfills the space between adjacent screens. The side bars and end portions of the screens may be made of wood, white metal, or any desirable material, and are preferably treated with suitable substances to prevent warping, rusting, etc. To facilitate the arrangement of the screens in the cabinet, the screens may be numbered or lettered according to their length, the shortest one being first inserted and adapted to rest on the lowermost stepped ledge.

60

Suitably supported by brackets secured to the bottom wall of the cabinet is a series of connected pipe sections 15 apertured, sub- 80

85

90

95

100

stantially as shown in Figure 4, with the openings extending upwardly toward the screens 13. One extremity of the pipe 15 is closed and the other extremity extends 5 upwardly, as shown at 15^a in Figure 3, to connect with the inner downturned end of the elbow coupling (see Figure 7) which extends outwardly through one of the trunnions 6 of the cabinet and is threaded at its 10 outer end to receive the nozzle 17 of a flexible pipe 18 connecting with a suitable blower or similar apparatus. Heated air is preferably blown through the flexible pipe 18, coupling 17, and apertured pipe sections 15 into the lowermost portion of the cabinet, whence it passes upwardly through the screens and the articles thereon, escaping through a vent 19 in the lid 9. If desired, steam or other drying agents may 15 be substituted for the heated air, or unheated air may be used, or a combination of air and a disinfectant or bleaching agent may 20 be forced through the pipes.

To hold the cabinet at any angular position 25 about its trunnions 6, I preferably provide a friction member 20 (see Figure 7) loosely encircling the trunnions and adapted to contact the outer wall of the cabinet, a spring 21, forcing the member against the cabinet 30 wall with sufficient pressure to prevent accidental swinging of the cabinet while clothes are being inserted or removed. Any desired tension of the spring 21 can be secured by turning the follower 22 threaded upon 35 the trunnion.

The operation of my improved drying apparatus is believed to be apparent. The articles to be dried are placed upon the screens, which are inserted into the cabinet 40 in the order of their length, the shortest screen being placed in the cabinet first, and so on, until all the screens are inserted or 45 sufficient screens to support all of the articles to be then dried. The lid is then closed and the cabinet swung into any convenient position. When the clothes are being inserted 50 the cabinet is most conveniently located in the dotted line position shown in Fig. 2 for then the screens are horizontal. After 55 the screens are packed, however, and the top closed, the cabinet may be swung into any position best suited for the room. The heated air or other drying agent is then turned on and passes through the porous fabrics of the screens and the articles supported thereon, and escapes with the moisture through 60 the vent. The current of heated air is continued as long as necessary or desirable for the drying operation, whereupon the current of air is turned off, the lid opened, and the screens and articles removed. If a 65 bleaching agent is forced through the pipe in place of heated air or a similar drying agent, the operation is substantially the same, the influx of the bleaching agent be-

ing continued until the desired effect has been secured.

To prevent undue radiation of the heated air, the walls of the cabinet may be lined with asbestos or other heat-insulating material, substantially as shown in Figure 7.

The arrangement of the side bars 14 of the screens as shown in Figure 5 makes it possible to dry sheets or similar articles of comparatively great length by winding them 75 around several of the screens, substantially as shown in Figure 8, wherein is shown a sheet or similar lengthy fabric A extending completely around the lowermost screen and then upwardly over the next adjacent screen. 80 The arrangement may be repeated with another sheet on the next two screens, or, if necessary, one sheet may be spread over three or more screens, the space between the side bars 14 and the cabinet walls being 85 ample to permit the desired winding.

While it will be apparent that the illustrated embodiment of my invention herein disclosed is well calculated to adequately fulfill the objects primarily stated, it is to be 90 understood that the invention is susceptible to variation, modification and change within the spirit and scope of the subjoined claims.

Having described my invention, I claim: 95

1. A drying apparatus comprising a frame, a cabinet rotatably mounted thereon, means for holding the cabinet in any angular position, the cabinet having an apertured pipe adjacent one wall for the introduction of heated air and the like and its opposite wall being formed with a vent for the outlet of the air and moisture, and a series of spaced screens for the support of the articles to be dried arranged between said 100 pipe and vent.

2. A drying apparatus comprising a frame, a cabinet rotatably mounted thereon, the cabinet having an apertured pipe adjacent one wall for the introduction of heated air and the like and its opposite wall being formed with a vent for the outlet of the air and moisture, friction means surrounding said pipe for holding the cabinet in any angular position, and a series of spaced screens for the support of the articles to be dried arranged between said pipe and vent. 110

3. A drying apparatus comprising a cabinet, a frame, trunnions on the cabinet rotatably mounted in the frame, one of said trunnions being apertured, a coupling extending through said apertured trunnion whereby an air pipe can be connected thereto, an apertured pipe within the cabinet connected to said coupling and arranged adjacent one wall for the introduction of heated air and the like and the opposite wall being formed with a vent for the outlet of the air and moisture, and a series of spaced 115 screens for the support of the articles to be dried arranged between said pipe and vent. 120

125

130

screens for the support of the articles to be dried arranged between said pipe and vent.

4. A drying apparatus comprising a cabinet rotatably mounted on a portable frame and having an apertured pipe adjacent one wall for the introduction of heated air and the like and its opposite wall being formed with a vent for the outlet of the air and moisture, two opposite walls of the cabinet

being formed with stepped ledges, and a series of screens for the support of the articles to be dried arranged to be supported upon said ledges between said pipe and vent.
